United States Patent Office

Des. 192,174
Patented Feb. 6, 1962

192,174

CUP

Bertrand N. Trombley, Birmingham, Mich., assignor to Bopp-Decker Plastics, Inc., Birmingham, Mich., a corporation of Michigan

Filed Mar. 23, 1961, Ser. No. 64,456

Term of patent 14 years

(Cl. D44—9)

FIG. 1 is a front elevational view of a cup showing
my new design;

FIG. 2 is a top plan view; and

FIG. 3 is a side elevational view thereof.

I claim:

The ornamental design for a cup, as shown.
